METHOD OF BENDING PIPE

Nathan Carl, Brooklyn, N. Y.

Application May 27, 1941, Serial No. 395,325

1 Claim. (Cl. 153—40)

This invention is a method for bending pipe in such manner that the pipe will not be crushed or distorted during the bending operation, but will retain its substantially normal cross section at the bend.

I am aware of Patent No. 2,119,875, issued on June 7, 1938, to my father, Louis Carl. In the pipe bending method and apparatus of that patent there is disclosed a mandrel composed of a succession of units of I-beam cross section successively secured to one another by interfitting links, rigid with the respective units in such manner as to permit cross axial flexing of the mandrel while all of the units of the mandrel are locked together against relative rotation. When a pipe is held against longitudinal movement and bent about a suitable former, the mandrel is adapted to be rotated and simultaneously moved longitudinally within the pipe to preclude crimping of the pipe throughout the bend and to maintain the cross section of the pipe substantially uniform.

The present invention operates in a different manner and utilizes a far more economical construction. In contradistinction to my father's patent, I employ a rigid mandrel composed, in effect, of a single rigid member to the end of which is attached a follower of the same diameter as the rigid mandrel. The mandrel is adapted to be rotated during the bending operation but is fixed against axial movement, while the follower is secured to the end of the mandrel by a ball and socket joint so that, when the mandrel is rotated, the follower does not rotate, but simply occupies the space within the pipe substantially equal to the normal interior pipe diameter and precludes crushing of the pipe at the point where the bend commences. In further contradistinction to the said prior patent, the present invention consists in moving the pipe axially, whereby it is drawn apast the mandrel and about the former to obtain the desired bend. The two methods are wholly distinct from one another and the apparatus employed operates in a different way. The present structure is much simpler than the prior construction.

Features of the invention, other than those adverted to will be apparent from the hereinafter detailed description and claims when read in conjunction with the accompanying drawing.

The accompanying drawing illustrates one practical embodiment of the invention, but the construction therein shown is to be understood as illustrative, only, and not as defining the limits of the invention.

Figure 1 shows a central section through the mandrel and the associated former with a pipe in the process of bending shown partially in central section and partially in elevation.

Figure 2 is a section through the pipe showing one end of the mandrel and with the connection between the mandrel and the follower in section. This view is taken in the plane of the line 2—2 of Figure 1.

Referring to Figs. 1 and 2 of the drawing, 1 designates an appropriate former mounted to rotate on a shaft 2. The former may be mechanically rotated through gears or other appropriate connections with any suitable prime mover, but, for the purpose of illustration, I have shown the rotating means in the form of a manually operable handle 3 of sufficient length to apply the necessary force. This handle is keyed to the shaft 2 to which the former 1 is also keyed. The periphery of the former is curved to provide a substantially semi-circular channel 4 into which one-half of the diameter of the pipe P is adapted to be received.

Positioned in substantially tangential relation to the base of the channel 4 of the former is a mandrel 5. This mandrel is shown as made up of two parts 5a and 5b. The parts 5a and 5b are of the same external diameter and they are arranged in coaxial relation to abut at the plane 6 where they may be threaded together or welded or both as may be desired, so as to become rigid with respect to one another and form collectively in effect one part. For the purpose of illustration, the sections 5a and 5b are shown as welded at 7. They collectively form a mandrel of somewhat greater length than diameter.

In the abutting faces of the sections 5a and 5b are formed collectively the socket 8 of a ball and socket joint. This socket is substantially spherical and from the base of the socket in the part 5b extends an outwardly tapering substantially frusto conical throat 9, so shaped as to permit of articulation of the shank 10 of the ball 11 which is fitted within the socket 8.

The shank 10 is rigidly secured to a follower 12. These parts may be attached together in any suitable way, but, for the purpose of illustration, the shank 10 is shown as passing through a central opening in the follower and welded to the follower at 13. The follower 12 is of substantially spherical section with parallel opposite faces, the diameter of the sphere being substantially the same as the diameter of the mandrel 5.

In the rear end of the mandrel 5 is a threaded socket 14 and into this threaded socket is screwed

a spindle 15, a right hand thread being shown in the drawing for this connection. The spindle 15 extends to an appropriate source of power whereby said spindle may be rotated in a counter-clockwise direction as viewed from the right hand end and as indicated by the arrow 16. The spindle 15 is, however, secured against axial movement, so that while it may rotate freely, it cannot move axially. This spindle thus constitutes the means for rotating the mandrel and holding it against axial movement. In practice the spindle 15 is made fairly long, so that the bend to be produced in the pipe may be made at some distance from its end.

To hold the mandrel in proper radial relation with respect to the former, a supporting block 17 is provided and this is adapted to straddle the pipe P directly adjacent a plane passing through the axis of the shaft 2 and perpendicular to the axis of the mandrel. This supporting block may be secured in place in any suitable way, but must be rigid enough to hold the pipe against the former. The pipe is adapted to be clamped to the former by means of a clamp 18 embodying a yoke 19 secured to the former 1 and adapted to be tightly forced against the pipe by a set screw 20. The clamp 18 has a semi circular face engaging the pipe and is adapted to embrace one-half the diameter thereof.

When it is desired to bend a pipe in the apparatus as shown, the former is moved into position to bring one face of the yoke 19 into engagement with the supporting block 17, these two contiguous faces then occupying a plane which includes the axis of the shaft 2 and which is perpendicular to the axis of the mandrel. This relation permits a straight pipe to be passed through the clamp 18 and through the block 17 while embracing the follower 12 and the mandrel 5. The pipe is pushed along in a right hand direction until the point of the pipe where the bend is to start reaches said perpendicular plane.

When the pipe has been brought into this position, the supporting block 17 is made rigid in a position for continued contact with the pipe and the set screw 20 is tightened to anchor the pipe firmly between the clamp 18 and the former, so that the pipe is rigidly secured to the former at this point which, as stated, is to be the point of the start of the bend.

After these conditions have been obtained, rotation of the shaft 15 is commenced and, while this shaft is rotating and imparting like rotation to the mandrel, the handle 3 is grasped and

5 moved in a counterclockwise direction, drawing with it the pipe P and causing the pipe to be bent about the former as indicated in Figure 1. The bend may be of any angular degree up to approximately 180 degrees. With a greater bend difficulty would be experienced in freeing the pipe from the former after the bend is finished.

10 During the bending operation the mandrel 5 continues to rotate and holds the pipe in distended position at the point of the start of the bend, so that it cannot crush at this point, where the greatest crushing strain generally occurs. The follower is not locked for rotation with the mandrel and simply occupies a position adjacent 15 the point of greatest crushing strain, so as to safeguard the pipe against crushing in this region.

15 After the pipe has been bent as desired, the clamp is released and the pipe is pulled free from the former in finished condition.

20 It will be found when bending pipes in the manner described and through the apparatus shown, that a uniform bend will be obtained and that the interior diameter of the pipe throughout the bend, as well as adjacent thereto, will be substantially uniform.

25 In the structure, hereinbefore fully explained, the mandrel is rotated, but the follower is not locked for rotation with the mandrel. This clearly distinguishes that form of the invention 30 from my father's patent wherein all the units which are enclosed within the pipe are rotated with the mandrel while the mandrel as a whole is longitudinally moved within the pipe during 35 the bending operation. According to the present invention the mandrel does not move axially but this movement is limited to one of rotation.

35 In the foregoing detailed description I have set forth the invention in its preferred practical 40 form, but the invention will be understood as fully commensurate with the appended claim.

Having thus fully described the invention, what I claim as new and desire to secure by Letters Patent is:

45 The herein described method which comprises drawing a pipe longitudinally about a former to produce a bend in the pipe, while rotating an axially stationary rigid sizing mandrel within the unbent portion of the pipe adjacent the start of the bend and maintaining a non-rotating sizing follower in stationary position within a bent portion of the pipe adjacent the start of the bend.

NATHAN CARL.
